FOLDING BENCH

Alexander J. Sturm, Stratford, Wis.

Application January 16, 1948, Serial No. 2,622

2 Claims. (Cl. 155—148)

1

This invention relates to an improved construction of folding bench and more particularly to a bench especially adapted for use by fishermen and which may be readily folded into a compact unit for carrying in an automobile or storage and which can be quickly and easily extended for use.

More particularly, it is an object of the present invention to provide a bench of extremely simple construction and which will effectively function to latch or lock itself in an extended position to eliminate any danger of the bench collapsing while in use.

Another object of the invention is to provide a novel construction whereby a back rest of the bench will function to effectively retain the legs in extended position and wherein the legs in turn will function as stops for limiting the movement of the back rest toward an extended position and for supporting the back rest when weight is applied thereto by the user or users of the bench.

Still a further and important object of the invention is to provide a bench especially adapted for use by fishermen and wherein the foot structure may be tilted for maintaining the seat in substantially a horizontal position when the bench is positioned on a sloping surface such as the bank of a river or creek.

Still a further object of the invention is to provide a bench especially adapted for use by fishermen and which is so constructed that it will not sink into sand or soft ground sufficiently to adversely affect the utility thereof.

Various other objects and advantages of the invention will hereinafter become more fully apparent from the following description of the drawings, illustrating a presently preferred embodiment thereof, and wherein:

Figure 1 is a front elevational view showing the bench extended;

Figure 2 is a bottom plan view of the extended bench;

Figure 3 is an end elevational view thereof;

Figure 4 is a vertical sectional view taken substantially along a plane as indicated by the line 4—4 of Figure 1;

Figure 5 is a fragmentary, exploded perspective view of a portion of the structure, and

Figure 6 is an end elevational view, partly broken away, of the extended structure.

Referring more specifically to the drawings, the novel folding bench or seat, constituting the invention, is designated generally 7 and includes a seat portion 8, a back rest designated generally 9, and two corresponding legs each designated generally 10.

The seat 8 is illustrated as being formed from a single relatively wide and solid member such as a board or plank but could obviously be formed of slats connected by braces and the back rest

2

9 is illustrated as including two slats 11 which extend longitudinally thereof and which are connected at their ends to end pieces or braces 12 having corresponding depending portions which extend to substantially below the inner or lowermost slat 11 and which depending portions are connected, intermediate of their ends, by hinges 13 to the upper side of the seat 8 adjacent the rear edge thereof, as best illustrated in Figures 3 and 4. The portions 14 of the end members or braces 12 which extend below the hinges 13 or are located on the opposite side of said hinges to the slats 11, are each provided with an elongated, longitudinally disposed notch 15 which opens outwardly of the terminal thereof and for a purpose which will hereinafter become apparent.

Each of the legs 10 includes a relatively wide, solid piece 16 which is preferably only slightly narrower than the seat 8 and which is hingedly connected to the under side of said seat and adjacent an end thereof by at least two hinges 17 which are arranged to be secured to the inner side of the leg portions 16 to permit said leg piece to fold inwardly and against the underside of said seat and so that when the leg piece 16 is extended to a position substantially perpendicular to the seat 8 the upper edge thereof will abut against the underside of the seat to prevent the leg piece 16 from swinging outwardly beyond its perpendicular position of Figure 1. As clearly illustrated in the drawings, the bench 7 is provided with a single leg 10 adjacent each end thereof and the bottom edges of said leg pieces 16 are arcuate and convex, as clearly illustrated at 18.

Each leg 10 also includes an elongated sill 19 which is connected intermediate of its ends by a fastening 20 to the complementary leg portion 16, said fastening 20 engaging said leg portion 16 intermediate of its side edges and adjacent to its arcuate bottom edge 18. The sills 19 are disposed so that one longitudinal edge thereof is disposed beneath or outwardly of complementary edge 18 and said sills are of a length substantially greater than the width of the leg portions 16 and are adapted to form the surface engaging portions of the legs.

In the embodiment of the invention as illustrated in Figures 1 to 5, each of the leg portions 16 is provided on its inner side and adjacent its forward edge with a block 21 from which projects a pin or stud 22 and which block is of approximately the same thickness as the sills 19. A latch bar 23 is pivotally mounted at 24 to the exposed side and adjacent the forward end of each sill 19 and said latch bars 23 are provided with notches 25 in one longitudinal edge thereof for selectively engaging the complementary stud 22, as best illustrated in Figure 4, for fixedly posi-

tioning the sill member relatively to the leg portion 16 on which it is pivoted and it will accordingly be readily apparent that said sill members may be adjustably disposed so that the bottom surface engaging edges thereof will be positioned either parallel to the plane of the seat 8 or at an angle thereto, as illustrated in Figure 4.

In the embodiment of the invention as illustrated in Figure 6, a slightly modified form of latching means for the sill members 19 is disclosed and wherein the studs 22a are threaded and the latch bars 23a are provided with elongated slots or openings 26, in lieu of the notches 25 for slidably receiving the studs 22a. Each stud 22a carries a clamping nut 27, preferably in the form of a wing nut which can be manually tightened for clamping the sills 19 at any desired angle with respect to the seat 8.

From the foregoing it will be readily apparent that the back rest 9 can be folded downwardly and inwardly on to the upper surface of the seat 8, as illustrated in dotted lines in Figure 3 and that in so moving the brace portions 14 will be swung out of engagement with the leg elements 16 and to the dotted line positions of Figure 3 so that said legs can be swung upwardly and inwardly against the underside of the seat 8 as indicated by the arrows in Figure 1 to thus afford a compact folded unit which may be readily carried in the trunk compartment of a vehicle or which may be readily stored or manually carried. It will be readily apparent that this folding of the bench 7 may be accomplished very quickly and easily and the opening and extending thereof can be accomplished with equal ease by first swinging the legs 10 outwardly to their extended position, as illustrated in Figures 1 and 2 after which the back rest 9 is swung upwardly and to the left from its dotted line to its full line position of Figure 3 to cause the notches 15 to engage the rear edges of the leg portions 16 and to thereby latch said legs 10 in extended position. Thus, the back rest 9 functions as a latch for the legs 10 and said legs in turn function as stops for limiting the extent that the back rest can be swung counterclockwise as seen in Figure 3 and to an extended position.

When the bench 7 is employed on a level surface the sills 19 are latched so that their bottom, surface engaging edges will be disposed substantially parallel to the plane of the seat 8 but when the bench 7 is utilized on a sloping surface such as the bank of a river, said sills 19 are adjusted so that their surface engaging edges are at an angle to the plane of the seat 8, as illustrated in Figures 4 and 6 in order that the seat 8 may be in substantially a horizontal position when the sills 19 are engaging a sloping surface.

The bench 7 may be formed of various materials, preferably wood except for the hinges and latch means and may be made in various sizes and it will be readily apparent that a chair or seat for one person may be constructed in the same manner as the bench 7 by merely reducing the length of the seat portion 8 and back rest 9.

Various other modifications and changes are likewise contemplated and may obviously be resorted to, without departing from the spirit or scope of the invention as hereinafter defined by the appended claims.

I claim as my invention:

1. An article of furniture comprising a seat, a leg hingedly connected to the underside of said seat and adjacent each end thereof for swinging movement upwardly and inwardly against the underside of said seat to a folded position, said legs being disposed in depending, substantially perpendicular relationship to the seat when in extended, operative positions, a back rest hingedly connected to the upper side of said seat adjacent the back edge of the seat and movable from a folded position against the upper side of said seat to an extended position at an obtuse angle thereto, and inter-engaging means on the legs and back rest, when said parts are in extended positions, for locking said legs in extended positions, each of said legs including a relatively wide piece which is hingedly attached to the seat and disposed transversely thereof, said back rest including brace members having portions depending below said seat, when the back rest is in an extended position, said depending portions having slots opening outwardly of their lower ends engaging corresponding edges of said leg members for latching the legs in extended positions and combining therewith to form said inner engaging means.

2. An article of furniture comprising a seat, a leg hingedly connected to the underside of said seat and adjacent each end thereof for swinging movement upwardly and inwardly against the underside of said seat to a folded position, said legs being disposed in depending, substantially perpendicular relationship to the seat when in extended, operative positions, a back rest hingedly connected to the upper side of said seat adjacent the back edge of the seat and movable from a folded position against the upper side of said seat to an extended position at an obtuse angle thereto, and inter-engaging means on the legs and back rest, when said parts are in extended positions, each of said legs including a relatively wide piece which is hingedly attached to the seat and disposed transversely thereof, said back rest including brace members having portions depending below said seat, when the back rest is in an extended position, said depending portions having slots opening outwardly of their lower ends engaging corresponding edges of said leg members for latching the legs in extended positions and combining therewith to form said inner engaging means, and said leg portions forming stops for limiting the swinging movement of the back rest toward an extended position.

ALEXANDER J. STURM.
